UNITED STATES PATENT OFFICE

THOMAS J. O'CONNOR, OF CHARLESTON, WEST VIRGINIA

TRANSMISSION

Application filed September 14, 1927. Serial No. 219,484.

The present invention appertains to a variable speed and power transmission apparatus in the form of a planetary-centrifugal fluid driving mechanism for transmitting power from a drive shaft to a driven shaft.

The apparatus is of the type embodying a compound planet gear or multiple compound planet gears actuated and fixed to the drive shaft and a centrifugal fluid impeller also actuated and fixed to the drive shaft, the fluid impeller being constructed so as to convey directional pressure to an outer drum which is connected to a pivot pinion that is free to rotate about the driven shaft, pivot pinion meshes with the planet gear and the planet gear meshes with a gear fixed to the driven shaft.

The principal object and novelty of the invention resides in the fact that the drive gears are always in mesh, the fluid receiver allowing changes of speed by infinite steps as greater or less power is required, as the load varies on the driven shaft and control means for receiving the driving power from the drive shaft to the driven shaft, the same control being adapted to hold the connecting parts in fixed position for direct drive.

A still further important object of the invention resides in the provision of a transmission apparatus of this nature which is comparatively simple in its construction, is automatic in taking heavy loads with reduced speed, has its parts compactly and conveniently arranged, has cushion effect between drive and driven shafts reducing shock of sudden loads, and is thoroughly efficient and reliable in its operation.

With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary longitudinal

vertical section through the apparatus embodying the features of my invention,

Figure 2 is a sectional elevation, the section portion being taken substantially on the line 2—2 of Figure 1,

Figure 3 is a fragmentary detail view taken substantially on the line 3—3 of Figure 1,

Figure 4 is a sectional elevation of the impeller,

Figure 5 is another sectional elevation thereof taken at right angles to that shown in Figure 4, and,

Figure 6 is a diagrammatic sketch showing the multiple compound gears and general scheme.

Referring to the drawing in detail, it will be seen that the letter A denotes an impeller somewhat similar to what is used in centrifugal pumps. This impeller is cast in one piece with a series of channels 5 with the blades 6 connecting the side walls, these blades being curved backward from the direction of rotation. The liquid enters near the shaft through entrances 7 and due to the curvature of the blades and the rotation the liquid is forced under pressure at the outer edge. This impeller is keyed or fixed to a drive shaft 8. The letter B denotes a disk with a bearing on the drive shaft and provided with teeth 10 at its outer edge for fitting in slots 11 in the drum 13. The drum is provided with a saw-tooth-like internal face 12 against which the fluid impinges from the impeller A. The teeth 10 fit in the slots 11 of the drum 13 journaled on the drive shaft and having an extension 14 fixed as at 15 to a plate 16 journaled on the driven shaft and having a pinion portion 17 which meshes with a gear 18 that has a pinion portion 19. The gear 18 is journaled on the shaft 20 supported by a bracket 21 in and to which the drive shaft 8 is fixed and driven shaft 22 is journaled. The gears 18, 19, coupled to the drive shaft, are to be considered the driving elements driven directly

5 by the drive shaft 8. A gear 23 is keyed or otherwise fixed to the driven shaft and meshes with the pinion 19. The disk B has a collar 24 operable by a suitable fork 25 and is normally urged in one direction by means of a spring 26 for varying the space between part 50 B and part 13 the teeth 10 in the slots 11 being always in mesh.

10 The operation of the transmission is as follows. The drive shaft 8 drives the impeller A and parts 21 and 20 in a positive direction. The resistance of the driven shaft 22 and the driven shaft gear 23 (under load) to rotation, causes the plate 16, drum 13 and 14 and the disk B through a ratio of multiple 55 compound gears 17, 18 and 19 to rotate in a reverse direction. The pressure of the fluid from the impeller A to the drum 13 and 14 and plate 16, causes the pinion 17 to be checked gradually from its reverse direction thereby imparting driving force in a positive direction to the gear 23 and the drive shaft 22. This occurs through the gears 19, 18 and 17 as a variable pivot for the positive driving force of 8, 21 and 20. The planet 60 bracket 21 functions as a positive (fixed) driving force and the receiver B through the parts above mentioned regulates the amount of force conveyed to the gear 23 fixed to the driven shaft 22, by regulation of the control fork 25. As the pinion 17 is checked in its negative or reverse rotation to a stopping point, then in a positive (forward) direction, the driven shaft approaches the speed of the 65 drive shaft as the pivot pinion 17 approaches the speed of the drive shaft. The fork 25 functions to space the disk B from the part 13 allowing a space for the escape of fluid under pressure from the impeller A, thereby allowing the drum 13 and 14, disk B plate 16 and pivot pinion 17 to slip to negative or reverse direction so as to release the driving force on the gear 23 which is fixed to the driven shaft 22. The rotation of the drive 70 shaft is spent in rotating the pivot pinion 17 and parts B, 13, 14, 15 and 16 in a negative direction and no driving force is applied to the driven shaft until the fork 25 allows the spring 26 to close the disk B in respect to the part 13 and the impeller builds up a pressure again, which requires but a few revolutions. The port 25 can also be regulated to allow the spring 26 to force the disk B against the adjacent face of the impeller A thus causing 75 a friction contact between the drive shaft 8 and the driven shaft 22 making a direct drive when desired, eliminating the fluid function and wear of the gears.

80 It is thought that the construction, operation, and advantages of the invention may be now understood without a more detailed description thereof. In the diagram shown in Figure 6, I have shown a multiplication of the gearing which may be used if desired.

85 The present embodiments of the invention

have been disclosed in detail merely by way of example since in actual practice they attain the features of advantage enumerated as desirable in the statement of the invention and the above description. It is apparent that in certain applications of this mechanism, reverse and forward rotation of the driven shaft will be required, in which case a reversing gear of some standard design would be constructed in the driven shaft. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:—

1. In a device of the character described comprising a casing with a quantity of fluid therein, a drive and driven shaft extending into the casing, an impeller fixed to the drive shaft, a drum including a gear journaled for rotation on the drive and driven shafts, a gear fixed to the driven shaft, a bracket 85 fixed to the drive shaft, a planet pin supported on the bracket and having its axis concentric with the driven shaft, planetary gears journaled on the planet pin meshing with the first and second mentioned gears, 90 and means slidably supported on the drive shaft and detachably engageable with the drum for locking the drive and driven shaft together thereby causing a direct drive.

2. In a device of the class described comprising a casing with a quantity of fluid therein, a drive and driven shaft extending into the casing, an impeller fixed to the drive shaft within the casing, a drum including a gear journaled on the drive and driven shafts independent of the impeller, a gear fixed to the driven shaft, a bracket fixed to the drive shaft, a planet pin supported on the bracket and having its axis concentric to the driven shaft, planetary gears journaled on the planet pin meshing with the first and second mentioned gears, the fluid force from the impeller resiliently effecting the power transmitted through the gearing aforementioned and the drum being adapted to alter the fluid force received from the impeller for sensitive regulation of the driven shaft when the drive shaft is in motion.

3. In a device of the class described comprising a casing with a quantity of fluid therein, a drive and driven shaft extending into the casing, an impeller fixed to the drive shaft within the casing, a drum including a gear journaled on the drive and driven shafts independent of the impeller, a gear fixed to the driven shaft, a bracket fixed to the drive shaft, a planet pin supported on the bracket and having its axis concentric to the driven shaft, planetary gears journaled on the planet pin meshing with the first and 120 second mentioned gears, the fluid force from the impeller resiliently effecting the power transmitted through the gearing aforementioned and the drum being adapted to alter the fluid force received from the impeller for sensitive regulation of the driven shaft when the drive shaft is in motion.

second mentioned gears, the fluid force from the impeller resiliently effecting the power transmitted through the gearing aforementioned and the drum being adapted to alter 5 the fluid force received from the impeller for sensitive regulation of the driven shaft when the drive shaft is in motion, said impeller being partly immersed in fluid and primed upon the initial starting of the drive shaft.

10 In testimony whereof I affix my signature.
THOMAS J. O'CONNOR.
